DESIGN FOR A HOUSE DRESS

Archie F. Keating, Decatur, Ill.

Application December 20, 1937, Serial No. 73,765

Term of patent 7 years

To all whom it may concern:

Be it known that I, Archie F. Keating, a citizen of the United States and a resident of Decatur, in the county of Macon and State of Illinois, have invented a new, original, and ornamental Design for a House Dress, of which the following is a specification, reference being had to the accompanying drawing.

I claim:

The ornamental design for a house dress, substantially as shown.

ARCHIE F. KEATING.
